LOCK

Harold Machinist, Long Island City, N. Y., assignor to Dudley Lock Corporation, Chicago, Ill., a corporation of Illinois

Application February 2, 1938, Serial No. 188,327

8 Claims. (Cl. 70—394)

This invention relates to the class of locks of the type known as cylinder locks, and is concerned with a novel method and means for "servicing" such locks, by which term is meant the opening of a lock without using the key particularly cut for that lock, required in instances when the key has been lost and there is no other way of opening the lock. While the method of servicing and the means therefor described herein may be used to open different types of cylinder locks, the following description is made with special reference to the lock described in United States Patent to George D. Full, No. 2,030,836, and known generally as the "Dudley lock."

The object of this invention is to provide a facile and quick method of servicing cylinder locks, such as the aforementioned Dudley lock, and to provide means for practicing such method.

For the attainment of these objects, and such other objects as may hereinafter appear or be pointed out, I have shown one embodiment of the said means in the accompanying drawing, in which—

Figure 1 is a longitudinal fragmentary sectional view of the lock in section, with the servicing tools of my invention in place therein;

Figure 2 is a cross-sectional view of the lock taken on lines 2—2 of Figure 1;

Figure 3 is a front view of the lock cylinder; 30 Figure 4 shows a regular key, in full view, for operating the lock;

Figure 5 is a sectional view of the key, taken on lines 5—5 of Figure 4;

Figure 6 shows a pair of servicing tools; and

Figure 7 illustrates a second pair of servicing tools, each bearing a different number or indicia and presenting different cam configurations, both figures being front views;

Figure 8 is a top view of a pair of servicing tools;

Figure 9 is a sectional view, taken on the line 9—9 of Figure 6, of the four complementing quarter tools;

Figure 10 is a top view of a single servicing tool formed in halves rather than in quarters.

The Dudley lock, more fully described in the said patent, includes a cylindrical casing 10 of annular form in which is mounted a rotary cylinder or plug 11 adapted for rotation therein under control of a plurality of tumbler elements 30 when actuated by key 35, Figure 4. The cylinder or plug 11 is made up of two longitudinally extending sections, indicated at 14 and 15, spaced apart by longitudinally extending plates 16 and provided with slots, respectively 14c and 15c, Figure 1, in which the said tumblers 30 slidably fit. As shown in Figure 1, there are four pairs of tumblers, each pair comprising a tumbler associated with each of the sections 14 and 15, 60

Figure 2. The tumbler elements when free are yieldingly projected by coil springs 32, Figure 2, into longitudinally extending grooves 10d, formed in the inner wall of the casing for locking engagement therewith.

The casing 10 is closed by a cap plate 20 which is secured to the cylinder or plug 11 so as to rotate therewith within the casing. The cap is formed with an opening 20b, Figure 3, corresponding to and registered with the key slot 11b formed in the rotary cylinder, Figure 2, for accommodating a key of a suitable size. The edge of each tumbler element adjacent the key slot 11b is provided with an abutment surface 30c adapted to be engaged by a cooperatively formed cam surface of the key 35, Figure 4.

These key abutment surfaces or shoulders are disposed for engagement by a key for causing movement of the tumbler elements in a direction against the reaction of their respective springs 32. As is well understood in the art, these tumbler elements are preferably formed different from each other in that their key-operated abutment shoulders 30c may be located at one of a plurality of predetermined positions from the end of the effective locking surface of the tumbler elements. The cam surface of the key for engaging the abutment surfaces of the tumbler elements have their contours shaped accordingly.

It will be manifest from the construction above described that the particular arrangement of the tumbler elements is such that certain of the tumbler elements of each series are movable in opposite directions from the others, and are engageable by different cam surfaces of a key. Likewise, the other series of tumbler elements are engageable by different cam surfaces of the key. The construction in effect provides four sets of independently operable tumbler elements, and to accommodate such construction, the key is provided with four longitudinally extending unrelated cam operating surfaces 35a, 35b, 35c, and 35d, for actuating the independent sets of tumbler elements of the respective series. Each of the cam surfaces of the key is of a sinuous contour and, as shown in the drawing, these surfaces are arranged in pairs at opposite edges of the key. As may be seen in the drawing, the operating portion of the key is of relatively flat stock, and for convenience the narrow top and bottom surfaces of the operating portion of the key are referred to as edges. Although the disclosure represents a preferred form of key, it is evident that the relative proportions of these narrow surfaces to the side surfaces of the key may vary widely.

The side walls of the key slot 11b, formed in the cylinder, are provided with additional wards consisting of embossments 14d and 15d, which are in the form of interrupted ribs which are

engageable in cooperating longitudinally extending ward grooves 35g and 35h, formed in the opposite side walls of the key. These embossments on the respective cylinder sections 14 and 15 are preferably of different size or shape, as seen in the drawing, and serve to assist in guiding the key when it is inserted into the lock, and ensures inserting the key in the lock in only one possible position. The cap plate 20, Figure 3, is formed with projections 20f and 20e, corresponding in outline, respectively, to wards 15d and 14d of the cylinder sections, Figure 2.

My method of servicing cylinder locks of the type described (i. e., having groups of tumbler elements, such as the group of four tumblers in the upper left, Figure 2 (designated I), the group of four in the upper right (designated II), the group in the lower right (designated III), and group (IV)) consists in taking up one group at a time and in manipulating the service tool to determine the combination and characteristics of that group of tumblers. My method contemplates a systematic investigation of the tumbler elements—one group at a time—by the use of a series of servicing tools used in a predetermined order. After determining the opening combination of one group of elements, the same procedure is followed to determine the combination of the other group. After which, the determined tool selected for each group are used together to open the lock.

A clearer understanding of this method will be gotten following a description of the servicing tools referred to. But before describing these tools, the structure of the regular keys will first be explained with reference to its section. The key section is shown in Figure 5 to comprise an upper and a lower recess 35f within which fit the ends of center plates 16—16, see Figure 3, and a left ward groove 35h within which fit the ward 15d of the cylinder, Figure 2, and the ward 20f of the cap plate 20, Figure 3, and a right ward groove 35g, Figure 5, within which fit the ward 14d of the cylinder, Figure 2, and the ward 20e of the plate cap, Figure 3. The cam surfaces 35a, 35b, 35c, 35d are variously positioned and dimensioned, as shown, in accordance with a particular individual combination. It is thus seen that the cam surfaces 35a operate upon the tumbler elements of group I, Figure 3; cam surfaces 35b operate upon group II; cams 35d, on III; and cams 35c, on IV.

In practicing my improved method of lock servicing as briefly outlined above, I provide a series or set of servicing tools, such as are shown in Figures 6 and 7. Each individual tool, to which the general designation 135 has been given, may be considered as a half or quarter part of the regular key, such as key 35 of Figures 4 and 5. The individual tools may be considered as having been formed from the key 35 as the result of two cuts, viz., a longitudinal cut centrally of the key, as viewed in Figure 4, to form an upper tool 135b, and a lower tool 135d, as viewed in Figures 6 and 7; and a cross cut longitudinally of the key, as viewed in Figure 5, to form a left tool 135a and a right tool 135b, as viewed in Figure 8. As a result of both cuts referred to, there are formed four "quarter" tools 135a, 135b, 135c, and 135d, Figure 9, each effective to operate upon the tumbler elements in, respectively, groups I, II, III, and IV, Figure 3.

It will be understood, however, that half-sectioned servicing tools, as may appear in Figures 6 and 7, may be employed above.

As best seen by comparing Figures 6 and 7 with Figure 4, the "quarter" tools, where these are used, are not formed by merely cutting the key in half along its longitudinal center, as viewed in Figure 4, but involves, in addition, the removal of at least that portion of the regular key body which forms the ward grooves 35g and 35h, Figures 4 and 5. Since the left wards 15d and 20f are made of a different size than the right wards 14d and 20e, more metal is removed between the left pair of quarter tools 135a and 135c, Figure 9, (distance 135L, Figure 9) than is removed between the right pair of quarter tools 135b and 135d (distance 135R, Figure 9).

A complete set of tools comprises a plurality of quarters, such as 135a, Figure 9, and insertable in the lock to operate upon the tumbler elements in group I, Figure 3, and a plurality of quarters for each of the other groups II, III and IV. That is, a complete set of tools may comprise four groups of quarters (though two may suffice for some purposes), the individual members of each group being formed to present different cam surfaces (136a, 136b, 136c, 136d, Figures 6 and 7) combinations, and each unit being consecutively numbered 137.

In servicing a lock in accordance with my improved method and using the servicing tools herein described, any one of the two or four groups of tumbler elements I to IV may be taken up first. We will assume that group I is first investigated. The individual segments, either the half or quarter tools of group I, are inserted into the lock, one at a time, and manipulated backward and forward and by a wiggling movement until the proper key segment or quarter, i. e., the one which will operate the tumbler elements of that group, is determined and which is ascertained by the limitation of movement of a pair of tumbler elements; is either laid aside or its number or indicia 137 noted. The next group, e. g., II, is then investigated and the proper key tool of group II selected. This is continued until the two segments or four quarter key parts are determined; by operating two or all four together, the lock may be opened.

Referring to Figure 9, it will be observed that a quarter tool 135a will fit in that portion of the key slot 20b, see Figure 3, which is associated with group I tumbler elements, with the bottom edge 138 of the tool riding on the top edge 38 of ward 20f and with lip 139 (depending from the lower portion of the tool) clearing to the right of ward 20f. This results from the fact that the metal (135L) corresponding to ward groove of the key (35g, Figures 4 and 5) has been removed from between the pair of tools 135a and 135c. In like manner and for the same reason, the other tool parts may be received in the key slot corresponding to the respective tumbler element group or quarter.

In trying one tool after another, in its proper tumbler group, the tool is manipulated forwardly and backwardly and wiggled in the key slot until the locksmith determines, principally by feel, certain characteristics of the tumbler elements which indicate to him the next best tool to try. This is continued until the proper segment or quarter tool is finally determined and as ascertained by the limitation of movement toward the periphery of the cylinder. To permit the tool to be wiggled or manipulated forwardly and backwardly in its key slot, it must not fit tightly in key opening 20b of the cap plate 20, Figures 3 and 1. For this reason, the shank 140 of the tool is cut

down a slight extent, so that the key will have a slight play when inserted in the proper quarter of key opening 20b. To facilitate tool manipulation, it is provided with depressions 141, Figures 1, 6, 7 and 10.

Specifically, as already inferred, instead of forming the tools as quarter parts of a key, the tools may be formed as half parts, as shown by the key tool 235, Figure 10. In this case, the tools may be formed by cutting a regular key in half (Figure 9) to form an integral upper half (135a and 135b) and an integral lower half (135c and 135d); the metal between the two halves may be removed in precise conformity with the left and right ward grooves (135L and 135R), so that the two key halves will have the outline shown in Figure 9. Or, the metal may be removed to an amount equal to the width of the larger of the two ward grooves; in this case, the half tool will rest upon the top ledge of the larger (20f, Figure 3) of the two wards 20f and 20e.

In this manner it will be observed that I have described and illustrated a servicing tool having tumbler operating cams independent of the guides or wards provided for the regular keys, so that by the method of applying wiggling, sliding and free manipulative pressure, the tumblers (elements 30) may be slid to the proper position for rotating the cylinder, the key combinations characteristics observed, and the lock opened without the regular key predeterminedly designed for the lock. It will be further observed that I have provided a servicing tool by the provision of tumbler camming elements having effective tumbler camming influence of large magnitude, by mounting camming elements so as to have wiggle clearance larger than the maximum camming displacement of the tumblers. The term "wiggle," "wiggling" or "wiggled" as herein used and as used in the claims is intended to denote a rocking or canting movement with or without a partial rotary action.

It will also be observed that I have provided a servicing tool which has variable sliding clearance within and into the seat of the lock within limits larger than the key regularly designed to open the lock.

It will also be observed that I have devised a new and novel method of servicing locks and for making the servicing tools.

While I have described and illustrated my invention in its preferred form by using all of the coordinated parts as achieving the desired results, it will be understood that portions thereof may be employed as to other novel features and therefore the scope of my invention is to be determined by the appended claims.

I claim:

1. As a new article of manufacture, a lock servicing tool including tumbler camming elements having effective tumbler camming influence of a magnitude to make available the camming influence of said elements along intermediate points on said elements formed as a quarter segment of a full key having ward engaging portions and having wiggle clearance when used in a lock with and in respect of the remaining segments.

2. As a new article of manufacture, a lock servicing tool including tumbler camming elements having effective tumbler camming influence of a magnitude to make available the cam-

ming influence of said elements along intermediate points on said elements formed as half segment of a full key having ward engaging portions and having wiggle clearance when used in a lock with and in respect of the remaining half segment.

3. As a new article of manufacture, a lock servicing tool including tumbler camming elements having effective tumbler camming influence of a magnitude to make available the camming influence of said elements along intermediate points on said elements and having said tumbler camming elements along the length thereof on one edge and ward engaging portions along the length thereof on the opposite edge and having sliding and wiggle clearance in the cylinder slot between the ward of said lock and the tumblers thereof.

20 4. For use in a cylinder lock having a plurality of tumbler elements arranged in groups, the herein described servicing means comprising individual tools arranged in a number of groups equal to the said tumbler element groups, the individual tools having cam projections operable upon the said tumbler elements, the said tumbler elements of each group presenting different combinations, and the individual tools of each group being of smaller dimensions than a key for said lock and presenting an assortment of cam projections operable upon different tumbler combinations, said camming projections having effective tumbler camming influence of a large magnitude to make available the camming influence of said elements along intermediate points on said elements whereupon by wiggling the same within the cylinder lock slot and the dimensions of the individual tools in respect of each other and the cylinder slot permitting wiggling of each of said tools in respect of each other.

25 5. The combination according to claim 4, wherein the lock comprises four groups of tumbler elements, and the said servicing means comprises four groups of individual tools.

6. The combination according to claim 4, wherein each group comprises four tumbler elements and wherein the said individual tools are provided with four cam positions.

7. The combination according to claim 4, wherein the said lock is provided with a key slot, and a ward projecting on two sides thereof, and wherein the said individual tools are formed with a portion adapted to rest upon the ledge of the said wards but movable in respect thereto by a wiggling action.

8. The servicing tool for combination with a cylinder lock having a plurality of tumbler elements, and a key slot for receiving a key having wards in respect to which the tumblers have a predetermined movement for permitting cylinder movement, said servicing tool comprising a segment fitting within said key slot and carrying tumbler camming elements on one part having effective tumbler camming influence of a large magnitude to make available the camming influence of said elements along intermediate points on said elements and other portions thereof said segments being smaller than said slot and being formed to permit wiggling of said means within said slot in respect of the wards of said lock and in respect of each other.

HAROLD MACHINIST.
